Primary Examiner—Philip S. Hyder(74) *Attorney, Agent, or Firm*—Daniel S. Song; Nixon Peabody LLP(57) **CLAIM**

The ornamental design for a hammer head, as shown and described.

DESCRIPTION

FIG. 1 is a frontal perspective view of a hammer head showing the new design;

FIG. 2 is a side profile view of the hammer head of FIG. 1;

FIG. 3 is a frontal view of the hammer head of FIG. 1;

FIG. 4 is a bottom view of the hammer head of FIG. 1; and, FIG. 5 is a rear perspective view of the hammer head of FIG. 1.

The broken line portions of the disclosure are for illustrative purposes only and form no part of the claimed design.
